UNITED STATES PATENT OFFICE

RALPH L. LEE, OF DAYTON, OHIO, ASSIGNOR TO DELCO-LIGHT COMPANY, OF DAYTON, OHIO, A CORPORATION OF DELAWARE

DOMESTIC APPLIANCE

Application filed October 23, 1923. Serial No. 670,380.

This invention relates to power driven washing machines of the movable tub type and has among its objects to permit stopping of the prime mover only when the tub is in a certain position.

In order to carry out this aim of the invention, a washing tub of the movable type has been provided, and an electric motor for driving the tub. A controller has been provided having manual means which when moved to one position causes the electric motor to be started, and when moved to another position conditions the controller to automatically stop the motor only when the tub is in a certain position.

Further objects and advantages of the present invention will be apparent from the following description, reference being had to accompanying drawings, wherein a preferred embodiment of one form of the present invention is clearly shown.

In the drawings:

Fig. 1 is a fragmentary view in end elevation of a laundry machine including the present invention, the tub being shown in one of its tilted positions with the power circuit closed.

Fig. 2 is a view in end elevation of the laundry machine, with the tub in horizontal position and the power circuit broken, the motor being shown diagrammatically.

Fig. 3 is a fragmentary detail view showing the method of mounting the push spring.

Referring to the drawings, a tub 20 has secured to each end thereof a shaft 21 for pivotally mounting the same between two end frames, one of which is indicated by the numeral 22. A return spring 23 is secured at one end to a stud 24 carried by frame 22, and the other end to a stud 25 carried by the tub 20. To shaft 21 is secured a crank arm 26 which is connected by a link 27 with a worm gear 28 mounted on a stud 29 supported by frame 22. A motor 30 is provided with brushes 31 and 32, and a motor shaft 33

carrying a worm 34 which meshes with worm gear 28.

The mechanism for permitting the motor 30 to be stopped only when the tub 20 is in a certain position, comprises a controller for the motor, means for starting the motor and for conditioning the controller to permit stopping of the tub, and means for permitting the controller to be actuated automatically to stop the prime mover only when the tub is in a certain position.

The controller comprises a stationary contact 40 mounted on the frame 22, and a movable contact 41 carried by an arm 42 secured to a lever 43 pivoted on a stud 44 carried by frame 22. Contact 40 is connected with a suitable source of current by wire 45, and contact 41 is connected with motor brush 31 by wire 46. Motor brush 32 is connected with the source of current by wire 47.

The means for starting the motor and for conditioning the controller to permit stopping of the tub, comprises a lever 50 pivoted on stud 44 and a push spring 51, one end of which is received by a socket 52 pivotally mounted on lever 50, the other end being received by a socket 53 pivotally mounted on lever 43.

The means for permitting the controller to be actuated automatically to stop the motor only when the tub is in a certain position, includes a sector 55 movable with the tub 20 and provided with a notch 56, and a detent or finger 57 carried by lever 43 and adapted to engage the notch 56.

Mode of operation

Fig. 2 shows the mechanism in normal position, and when it is desired to start the washing machine, the controller is operated by moving the lever 50 to the full line position shown in Fig. 1. When the lever 50 is in this position, the spring 51 bearing against the lever 43 will cause lever 43 to be rotated on its pivot 44, thereby closing contacts 40

80

85

90

and 41, and lifting the finger 57 out of the notch 56 in sector 55. Spring 51 will maintain the contacts 40 and 41 closed regardless of the position of the tub 20, and the motor circuit will be from the source of current through wire 45, contact 40, contact 41, wire 46, brush 31, motor 30, brush 32, wire 47 back to the source of current.

When it is desired to discontinue operation of the washing machine, the lever 50 is moved to the dotted line position shown in Fig. 1, for conditioning the controller to permit stopping of the tub. The spring 51 will now tend to open the contacts 40 and 41. However, should the tub 20 be in one of its tilted positions, such as shown in Fig. 1, at the time the lever 50 is moved in an attempt to stop the motor 30, the finger 57 bearing against the edge 61 of sector 55 will prevent the contacts 40 and 41 from being separated. Edge 60 of sector 55 serves the same purpose as edge 61 when the tub 20 is tilted in an opposite direction. As the tub 20 approaches the position shown in Fig. 2, the spring 51 will force the detent or finger 57 into the notch 56 and thereby automatically actuate the controller by separating the contact 41 from contact 40 to stop the motor 30. The finger 57 engaging the edges of notch 56 will stop the tub 20 in substantially horizontal position, as shown in Fig. 2.

While the form of embodiment of the invention as herein disclosed, constitutes a preferred form, it is to be understood that other forms might be adopted, all coming within the scope of the claims which follow.

What is claimed is as follows:

1. A washing machine comprising, in combination, a movable tub, a power device, connections between the power device and tub for driving the latter, a controller for the power device, means for conditioning the controller to effect continuous operation of the tub or to permit stopping of the tub, and means for permitting the controller to be actuated automatically to stop the power device only when the tub is in a certain position.

2. A washing machine comprising in combination, a movable tub; a power device drivingly connected to the tub; a sector secured to said tub; a detent normally engaging the sector to lock the tub in a proper inoperative position; means manually operable to one position to disengage the detent from the sector and hold it in such disengaged position and to start said power device, and movable into another position to reverse its effect upon the detent and cause it to engage the sector and stop the power device when the tub assumes the proper position.

3. A washing machine comprising in combination, a movable tub; a power device; connections between the power device and tub for driving the latter; a controller for the

power device; a notched sector carried on the connections between the power device and the tub; a detent normally engaging the notched sector to lock the tub in the proper inoperative position; and manually operable means including a spring so constructed and arranged that when operating in one position said spring tends to hold said detent out of engagement with the notch of the sector and the power device will start to operate the tub, and when moved to the other position the spring will exert pressure upon the detent to cause it to engage with the notch of the sector thereby stopping the power device and locking the tub in its proper inoperative position.

4. A washing machine comprising, in combination, a movable tub, an electric motor, connections between the motor and tub for driving the latter, an electric switch for the motor, a spring, a manually operable member for positioning said spring with respect to said switch whereby to apply spring pressure in one direction to start the motor and in another direction for conditioning the switch to cause automatic stopping of the motor, and means movable with the tub for preventing operation of the spring to open the switch except when the tub is in a certain position.

5. A washing machine comprising, in combination, a movable tub, an electric motor, a motor switch, connections between the motor and tub for driving the latter, and means for preventing opening of the motor switch except when the tub is in a certain position.

6. A washing machine comprising a tub, supporting means for the tub, an electric motor, driving connections between said tub and motor for moving said tub, a single manually operable switch for starting and stopping the motor, and means associated with the tub and cooperating with the switch for preventing said switch from stopping said motor except when predetermined relationship is established between said tub and supporting means.

7. A washing machine comprising a tub, supporting means for the tub, an electric motor, driving connections between said tub and motor for moving said tub, a single manually operable switch for starting and stopping the motor, and means associated with the tub and cooperating with the switch for preventing said switch from stopping said motor except when predetermined relationship is established between said tub and supporting means and for locking said tub in the position at which it stopped.

8. A washing machine comprising a tub, a motor drivingly connected to said tub, a manually operable switch for stopping said motor by a snap action in said switch and means for preventing the operation of said snap action except at one, at least, selected position of said tub.

9. An electric switch comprising a lever, an electrical contact arm, a spring urging said lever and arm apart, said lever being movable to two positions to urge said arm, respectively, into or out of electrical contact.

5 10. An electric switch comprising a lever, an electrical contact arm, a spring urging said lever and arm apart, said lever being movable to two positions to urge said arm, respectively, into or out of electrical contact and pivoted sockets for the ends of said spring.

10 In testimony whereof I hereto affix my signature.
